HYDRAULIC ABUTMENT DEVICE

Filed Sept. 19, 1934

UNITED STATES PATENT OFFICE

2,136,080

HYDRAULIC ABUTMENT DEVICE

Joseph F. Joy, Claremont, N. H., assignor to Sullivan Machinery Company, a corporation of Massachusetts

Application September 19, 1934, Serial No. 744,703

4 Claims. (Cl. 60—52)

My invention relates to fluid operated extensible supports, and more particularly to hydraulically operated posts for use as mine props or the like.

An object of my invention is to provide an improved fluid pressure operated extensible supporting device. Another object of my invention is to provide an improved hydraulically operated post or group. A further object of my invention is to provide in a hydraulic prop improved operating and controlling means. Other objects and advantages of my invention will hereinafter more fully appear.

In the accompanying drawing, in which one embodiment of the invention is shown for purposes of illustration,—

Fig. 1 is a central vertical section through the illustrative embodiment;

Fig. 2 is a fragmentary view on a section corresponding to the section of Fig. 1, but showing parts in different relation, and

Fig. 3 is a fragmentary sectional view showing a conventional slip device.

Referring to the drawing, it will be observed that a bottom plate or abutment 1 supports in rigid relation thereto a cylinder 2 having an upper head 3 traversed by a bore 4 through which a hollow member 5 is slidably movable. The member 5 corresponds to a piston rod and is connected at its lower end 6 to a piston member 7 having a suitable packing 8. A sealing ring 9 is carried by the head 3. The upper end of the member 5 supports an abutment or plate 10 which is, in the embodiment of the invention shown, adapted to engage a mine roof or the like.

In the collapsed position of the parts shown in Fig. 1 a substantial quantity of liquid, preferably an oil of suitable viscosity, is enclosed within the bore of the hollow member 5 and this is intended to be displaced from the space within the interior of the member 5 to the space within the cylinder 2 below the piston 7, in order to effect extension of the jack or post. For this purpose there is arranged, herein integrally with piston 7, a central upwardly extending cylinder member 12 having a bore 13 in which a suitable pump plunger 14 is reciprocably mounted. The bore 13 communicates, at a point adjacent the lower end of the stroke of the plunger 14, with a valve chamber 15 through a port 16, the valve chamber 15 containing a ball valve 17 cooperating with a seat 18 to permit the drawing-in of liquid from the interior of the member 5 through a suction port 20, while preventing reverse flow.

The extreme bottom of the bore 13 communicates

through a port 21 surrounded by a valve seat 22 and controlled by a spring loaded ball valve 23 with a chamber 24 in which the ball valve and its spring 25 are mounted; and the chamber 24 is provided with a discharge port in the form of an opening 26 through a closure plug 27 so that fluid forced through the opening 21 and past the valve 23 may be discharged through the opening 26 into the space below the piston 7.

The plunger 14 is connected by a pitman 30 with a crankpin 31 upon a crank disc 32 suitably supported upon a drive shaft 33, which is rotatably mounted in a bushing 34 in a cover plate 35 secured to the member 5 at an appropriate position. A suitable packing 36 surrounds the shaft 33. Shaft 33 supports a polygonal socket 37 at its outer end, and with this the driving element 38 of a suitable operating motor 39 is adapted to be connected to rotate the shaft 33 and to operate the pump plunger 14. The motor 39 may desirably have between it and its terminal driving element 38 a slip friction mechanism, for example, as shown at 60 in Fig. 3, to permit slippage when the abutment plate 10 reaches and is forced solidly against the surface which it is intended to engage. Other suitable expedients for preventing excessive shocks and sudden stoppage of the motor may be resorted to, as, for example, the arrangement of a slipping clutch such as that shown in Figure 3, between the drive socket member 37 and the crank disc 32.

Parallel to the chamber 24 there is arranged a second chamber 40 in the piston member 7. This chamber contains a ball valve 41 normally held seated by a spring 42 and controlling flow between the chamber 40, whose lower end is connected by a passage 43 with the space below the piston 7, and a passage 44 which extends through the upper end of the piston member 7 and communicates with the space within the interior of the member 5. In suitable guides 45 a plunger rod 46 is mounted in a position to extend freely into engagement with the ball valve 41, and a sleeve 47 is slidably mounted upon the pump cylinder element 12 and has a collar 48 for engaging the upper end of the plunger rod 46. A spring 49 engages the lower end of the sleeve 47 and also engages a shoulder 50 on the piston member 7, whereby the sleeve 47 is normally held in a position such that the plunger rod 46 will not unseat the ball valve 41. A link 52 pivotally connected at 53 to the sleeve 47 is pivotally connected at its upper end to a crankpin 54 upon a shaft 55 which projects through a suitable stuffing box 56 formed in the wall of the mem-

55

ber 5, and a wrench or handle may be applied to the extremity 57 of the shaft 55 to enable rotation of the latter and thereby movement of the pin 54 to move the link 52 downwardly and thereby depress the sleeve 47 far enough to cause the plunger rod 46 to be engaged and to be moved downwardly to unseat the ball valve 41 and thereby to open a free communication between the opposite sides of the piston 7.

10 The mode of operation of the device will be readily apparent from the foregoing description. The extensible post is brought into the position where it is desired to have it used and is set upright upon a mine bottom, for example. The 15 driving motor is then connected through its driving element 38 with the drive socket 37 and the shaft 33 is rotated. This causes the crankpin 31 and connecting rod 30 to reciprocate the plunger 14, and liquid is forced from the chamber within the member 5 to the space below the piston 7, the liquid being drawn in on the up-strokes of the plunger 14 through the inlet port 20 and past the valve 17 and through the port 16 into the cylinder bore 13, and being forced 20 on the downward strokes of the plunger 14 through the port 21 past the ball check valve 23 and through the port 26 into the space below the piston 7, and the latter is moved upwardly. When the plate 10 engages the roof, a yielding 25 mechanism such as has been described will preclude breakage of the parts or sudden stoppage of the motor.

Obviously the post will remain in its extended position, provided the valves 23 and 41 seat properly, just as long as is desired. When it is desired 30 to release and lower the post, the operator may rotate the shaft 55 with a wrench or handle applied at 57, thereby causing the drive pin 54 to move the link 52 downwardly, thereby depressing the sleeve 47 and moving the plunger 46 down to unseat the valve 41. The weight of the parts will then cause the piston 7 and member 5 to move 35 downwardly, while the liquid below the piston 7 will pass up through the port 43, chamber 40 and port 44 and into the interior of the member 5 again.

From the foregoing description it will be evident that I have provided a very simple, compact, rugged and easily controlled extensible device, 40 which is well adapted to use either as a hydraulic jack or as a mine prop or for various other purposes which will suggest themselves to those skilled in the art. Due to the use of a liquid, a rigid holding is effected, and due to the detachable driving element the cost of the units may be kept 45 low. A simple and positive device for permitting collapse of the prop or jack will be noted to be provided and the entire device is wholly without parts which are subject to easy derangement or likely to be broken during use or handling of the apparatus.

While there is in this application specifically described one form which the invention may assume in practice, it will be understood that this 50 form of the same is shown for purposes of illustration and that the invention may be modified and embodied in various other forms without departing from its spirit or the scope of the appended claims.

70 What I claim as new and desire to secure by Letters Patent is:

1. In combination, in an apparatus of the character described, a cylinder member, a piston member reciprocable therein, each of said members having an abutment element associated

therewith, a pump carried by said piston and having a cylinder fixed with respect to the latter for displacing fluid from one side of said piston to the other, a fluid displaceable by said pump, means controlling reverse flow of said fluid, and 5 controlling means for said reverse-flow-controlling means including an element surrounding said pump cylinder and movable axially of the latter to enable such reverse flow.

2. In a hydraulic mine column, in combination, 10 an outer cylinder, a piston contained in said outer cylinder and having a tubular piston rod extending through the outer head of the cylinder and providing a fluid reservoir, said cylinder and piston relatively reciprocable and respectively having means at their remote extremities engageable with extraneous abutments, means for pumping fluid from said reservoir to said outer cylinder to act between said outer cylinder and said piston to effect relative movement of said piston and 15 cylinder comprising a pump cylinder mounted on said piston and arranged within said tubular piston rod and submerged within the fluid in the reservoir, a movable pump element contained in said pump cylinder, pump intake and discharge 20 passage means in said pump cylinder and said piston for conducting fluid from said reservoir to said outer cylinder, intake and discharge valves controlling said passage means, a pump driving member mounted on said piston rod and 25 engageable exteriorly of said piston rod with suitable driving means and connected interiorly of the piston rod with said movable pump element, by-pass valve means in said piston for by-passing the fluid from the outer cylinder to said reservoir within said piston rod, said by-pass valve 30 means distinct from said pump intake and discharge valves, and an operating member mounted on the piston rod at a point remote from said by-pass valve means and operable from exteriorly 35 of the piston rod for controlling said by-pass valve means, said by-pass valve means controlling member having connections within said piston rod for operating said by-pass valve means including a reciprocable valve operating member 40 coaxial with and guided on said pump cylinder.

3. In a hydraulic mine column, a base having a bottom abutment engaging member and an integral outer cylinder, a piston reciprocable in 45 said cylinder and having an elongated tubular piston rod extending upwardly through the outer head of the cylinder and providing a fluid reservoir, said piston rod having at its upper extremity an abutment engaging member, means for pumping fluid from said reservoir to said outer cylinder beneath said piston to act on said piston to effect relative movement between said piston and outer cylinder comprising a pump cylinder mounted on said reciprocable piston and arranged within said tubular piston rod, a movable pump 50 element contained in said pump cylinder, pump intake and discharge passage means in said piston and pump cylinder for conducting fluid from said reservoir to said outer cylinder beneath said piston, intake and discharge valves controlling 55 said passage means, a horizontal driving member journaled in the wall of said piston rod near the upper extremity of the latter and engageable exteriorly of said piston rod with suitable driving 60 means and connected interiorly of the piston rod with said movable pump element, by-pass valve means in said piston for by-passing the fluid from the outer cylinder beneath said piston back to said reservoir within said piston rod, said by-pass 65 valve means distinct from said pump intake and discharge valves, and an operating member mounted on the piston rod at a point remote from said by-pass valve means and operable from exteriorly 70 of the piston rod for controlling said by-pass valve means, said by-pass valve means controlling member having connections within said piston rod for operating said by-pass valve means including a reciprocable valve operating member 75 coaxial with and guided on said pump cylinder.

valve means distinct from said pump intake and discharge valves, and means for operating said by-pass valve means including an operating member surrounding and guided on the pump cylinder 5 and a horizontal rotatable member journaled in the wall of the piston rod in adjacency to said driving member for said movable pump element and engageable exteriorly of the piston rod with suitable rotating means and connected interiorly 10 of the piston rod with the operating member for said by-pass valve means.

4. In an extensible mine column, in combination, relatively reciprocable inner and outer telescopically arranged column elements, one in the 15 form of a cylinder and the other having a piston secured thereto, said piston contained in said cylinder, said telescopic column elements having means at their remote extremities engageable with extraneous abutments, the reciprocable column element providing a fluid reservoir, and means for pumping fluid from said reservoir to 20 said cylinder to act on said piston to effect extension of said column elements comprising a pump carried by the reciprocable column element 25 and submerged in the fluid in the reservoir there-

in, said pump including a cylinder containing a piston and having driving means arranged within said reciprocable column element, means carried by said reciprocable column element and engageable exteriorly of said column element with 5 suitable driving means and connected interiorly of said reciprocable column element with said pump driving means, by-pass means including a by-pass valve distinct from said pump and carried within the piston of said reciprocable column 10 element for by-passing the fluid from said cylinder beneath said piston back to said reservoir to effect collapse of the column elements, operating means for said by-pass valve comprising an operating element coaxial with the pump and 15 guided on the pump cylinder, and operating-element-actuating means carried by said reciprocable column element at a point remote from said by-pass valve and having exteriorly of said column element an actuating portion and connected 20 interiorly of said reciprocable column element with said operating element of the operating means for said by-pass valve.
